(57) CLAIM

The ornamental design for a surface configuration of a door handle for a vehicle, as shown and described.

DESCRIPTION

This application is related to co-pending Applications Ser. Nos. 29/210,444, 29/210,443, and 29/210,445, all respectively entitled Surface Configuration of a Vehicle, Toy and/or Other Replicas.

FIG. 1 is a front view of a first embodiment of a surface configuration of a door handle for a vehicle according to my novel design;

FIG. 2 is a top view of the first embodiment of the surface configuration of a door handle for a vehicle according to my novel design;

FIG. 3 is a right perspective view of the first embodiment of the surface configuration of a door handle for a vehicle according to my novel design;

FIG. 4 is a front view of a second embodiment of the surface configuration of a door handle for a vehicle according to my novel design;

FIG. 5 is a top view of the second embodiment of the surface configuration of a door handle for a vehicle according to my novel design; and,

FIG. 6 is a left perspective view of the second embodiment of the surface configuration of a door handle for a vehicle according to my novel design.

The broken lines are for illustrative purposes only and form no part of the claimed design.
